UNITED STATES PATENT OFFICE.

FREDERICK MALCOLM REID, OF DETROIT, MICHIGAN, ASSIGNOR TO FRUEHAUF TRAILER COMPANY, OF DETROIT, MICHIGAN, A CORPORATION OF MICHIGAN.

TRAILER LOCK.

Application filed February 21, 1925. Serial No. 10,747.

REISSUED

To all whom it may concern:

Be it known that I, FREDERICK MALCOLM REID, a citizen of the United States, residing at Detroit, in the county of Wayne and State 5 of Michigan, have invented certain new and useful Improvements in Trailer Locks, of which the following is a specification.

This invention relates to center locking devices for trailers. It is the object of the 10 invention to provide a simple, strong, sturdy lock of an automatic character, in which the automatic feature may be simply discontinued by throwing a lever from one side to the other. This will be more fully explained 15 hereinafter.

In the drawings:

Fig. 1 is a fragmentary side elevation of a trailer equipped with the improved center lock.

Fig. 2 is a fragmentary front elevation showing the lock.

Fig. 3 is a vertical section taken on the line 3—3 of Fig. 2.

The trailer is provided with a drawhead 25 *a*, which is provided with an integral lock table *b* and is provided at the center with a keeper socket *c*. A spring-pressed vertically guided bolt *d* is slidable in the bolt housing *e*, which is riveted to the chassis 30 frame of the trailer. The keeper socket and the lock table, which are part of the drawhead, are riveted to the frame of the truck, or what we sometime call the "gear frame".

The coil spring *f* engages against the 35 shoulder on the bolt head and within the bolt socket and tends to project the bolt. On the top of the bolt housing is located a lever *h* which has an eccentric fulcrum *g* secured to the upper end of the bolt by means of the 40 pivot pin *i*. The pivot pin is eccentrically located on the circular fulcrum or roll of the lever at substantially a 90-degree point with respect to the attachment of the lever to this roll or fulcrum. Now obviously by simply 45 throwing the lever over from the position shown in the full lines to the position shown in the dotted lines in Fig. 2, the lock is taken from the position of action to the position of inaction. It will be seen that in the position 50 shown in the full lines the lever, together with the roll fulcrum, can rise above the bolt bracket when the lower end of the bolt slides along the table. When the gear frame reaches center position with respect to the 55 chassis frame, the lock will automatically

shoot into the keeper socket. This makes a very strong lock which can be easily manufactured and applied to the chassis frame. The lock itself is a separate unit which may be manufactured as a unit and riveted as a 60 unit to the chassis frame. The keeper socket simply is an integral part of the drawhead as is also the table along which the lock slides.

What I claim is:

1. A center lock for vehicles, having in combination an upper member, a lower member, with two members arranged to have relative movement with respect to each other, a bolt guide housing on the one member, a 70 table provided with a center keeper socket on the other member, a sliding bolt guided in the bolt guide and tending to project into the keeper socket when lined up therewith, and means connected with the outer end of the sliding bolt and operating in direct connection with the bolt guide housing to either release the bolt for automatic projection into the keeper socket or else to set the bolt 75 against projection into the keeper socket. 80

2. A center lock for vehicles, having in combination an upper member, a lower member, the two members arranged to have relative movement with respect to each other, a bolt guide housing on the one member, a 85 table provided with a center keeper socket on the other member, a sliding bolt guided in the bolt guide and tending to project into the keeper socket when lined up therewith, and a lever which can be thrown from one 90 side to the other and which is connected at the outer end of the bolt and operates in direct connection with the bolt guide housing for throwing the bolt out of operation 95 or releasing the bolt for automatic projection into the keeper socket.

3. A center lock for vehicles, having in combination an upper member, a lower member, the two members arranged to have relative movement with respect to each other, a bolt guide housing on the one member, a table provided with a center keeper socket on the other member, a sliding bolt guided in the bolt guide housing and tending to project into the keeper socket when lined up therewith, and a lever having a roll-like fulcrum eccentrically connected with the outer end of the bolt and bearing against the guide housing so that by throwing the lever to the 100 one side of center the bolt is held out of 105 110

operation and turning it to the other side of center the bolt is released for automatic projection into the keeper socket.

4. A lock for trailers and gear frames, having in combination with a trailer and a gear frame, a lock guide bracket which can be secured to the trailer frame, a bolt guided vertically in said bracket, a spring for projecting the bolt downwardly, a table pro-

vided with a center keeper socket secured to the gear frame, and a lever having a roll-like fulcrum bearing on the top of the bolt guide bracket and having an eccentric pivot connection with the upper end of the bolt.

In testimony whereof I have affixed my signature.

FREDERICK MALCOLM REID.
